UNITED STATES PATENT OFFICE.

CHARLES H. CUNNINGHAM, OF OAKLAND, CALIFORNIA.

DESIGN FOR A STREET-LIGHTING STANDARD.

Application filed October 17, 1928. Serial No. 28,522. Term of patent 3½ years.

To all whom it may concern:

Be it known that I, CHARLES H. CUNNINGHAM, a citizen of the United States, residing at Oakland, in the county of Alameda and State of California, have invented a new, original, and ornamental Design for a Street-Lighting Standard, of which the following is a specification, reference being had to the

accompanying drawing, forming a part thereof.

The figure is a side elevation of the street lighting standard, showing my design.

I claim:

The ornamental design for a street lighting standard, as shown.

CHARLES H. CUNNINGHAM.
